UNITED STATES PATENT OFFICE

DOWNS SCHAAF, OF COLUMBUS, OHIO, ASSIGNOR TO THE STITT IGNITION COMPANY,
OF COLUMBUS, OHIO, A CORPORATION OF OHIO

SEAL FOR SPARK PLUGS

Application filed May 17, 1929. Serial No. 363,770.

According to the common practice at present the battery or generator electrode of a spark plug is mounted in a porcelain insulator, the sealing between the electrode and the insulator being effected by means of a cement of silica and silicate of soda. The cement referred to contains more or less water and such a sealing is not uniformly successful because of the creepage of the cement and a resultant leakage of cylinder gases and cracking of the porcelain.

It is therefore, the aim of this invention to provide a seal that shall not be subject to such objections. Because the metal bismuth has the property of expanding when changed from a liquid to a solid state and because the melting point of that metal is 518° Fah. and such temperature is not reached in the porcelain insulator of a spark plug at the exposed portion where the seal is to be applied I use that metal or a suitable alloy thereof to effect the sealing.

In the accompanying drawings—

Figure 1 is a sectional view of the shell 25 of a spark plug with the porcelain insulator containing my improvement shown in full.

Fig. 2 is a sectional view of the porcelain insulator showing my seal applied to the electrode wire.

30 In the views 5 designates the metallic shell which is of ordinary form and construction; 6 the porcelain insulator, and 7 the electrode wire, the latter being provided with an enlarged and threaded end for the electrical connections.

On the electrode wire 7 just below the threaded end thereof I mold a sleeve 8 of bismuth or a suitable alloy of bismuth. This molding is effected by pouring the molten 40 bismuth or an alloy thereof into the insulator while the electrode is positioned therein.

The porcelain, in the instance shown, is at its upper end and before baking formed with an internal threaded socket of larger diameter than the diameter of the wire of the electrode and into this socket around the wire the bismuth or alloy thereof is poured as before stated. However the seal may be applied in other obvious ways. The wire 7 at the portion where the seal is applied is roughened or

flattened so that the seal will stick thereto and movement thereof in the seal prevented. The threaded character of the seal is designed and adapted to prevent movement of the seal in the porcelain but any other external form of the seal and of the wire at the locale of the seal can be used that will prevent such movement.

Particular advantages, among others, of a metallic seal such as described is that, first, 60 it is gas tight as compared with a ceramic seal, second, it remains in the position applied whereas a ceramic seal such as referred to creeps toward the nose of the insulator and on expansion at such point of the seal often causes cracking of the insulator, third, 65 economy of time and labor in manufacture of the seal.

A further decided advantage of bismuth as compared with the cement as the sealing 70 material is that the metal has no corrosive effect whereas with cement the wire is sometimes destroyed and rendered useless by the corrosive action of the cement.

The forms and assembling of the parts 75 can be changed without departing from the gist of the invention as claimed.

What I claim is:—

1. The combination of a spark plug whose electrode and insulator are secured in gas 80 tight relation by a bismuth seal.

2. The combination of a spark plug whose electrode and insulator are secured in gas tight relation by a bismuth seal located in the exposed portion of the spark plug.

3. In a spark plug the combination of an insulator, an electrode therein, and a seal securing them in gas tight relation consisting of bismuth or an alloy thereof that expands on solidification.

DOWNS SCHAAF.
